CATAMENIAL SHIELD

Ronald Gordon Altrows, 320 Harris St.,
Ville St. Laurent, Quebec, Canada

Filed July 23, 1973, Ser. No. 381,920

Term of patent 14 years

Int. Cl. D24—99

U.S. Cl. D83—1 J

The figure is a perspective view of a catamenial shield showing my new design, the outer surface of the oval side being similar to the outer surface of the narrow band side.

I claim:

The ornamental design for a catamenial shield, as shown and described.
